UNITED STATES PATENT OFFICE.

FREDERICK MEYER, OF BUFFALO, NEW YORK, ASSIGNOR TO MEYER BODY CO. INC.,
OF BUFFALO, NEW YORK, A CORPORATION OF NEW YORK.

REFRIGERATING APPARATUS.

Application filed July 25, 1924. Serial No. 728,127.

This invention relates to a refrigerator which is more particularly designed for use on a wagon whereby ice cream is delivered from a factory to customers.

5 It is the object of this invention to provide a refrigerator of this character which is comparatively simple, durable and inexpensive in construction, which permits of readily maintaining the goods at the desired 10 cooling temperature with a minimum expenditure of ice, and which can be easily replenished with ice when required and conveniently cleaned for keeping the refrigerator in the most sanitary condition.

15 In the accompanying drawings:—

Figure 1, is a side elevation of an ice cream delivery wagon embodying my improvements.

Figure 2, is a horizontal section, on an 20 enlarged scale, taken on line 2—2 Figure 1.

Figure 3, is a vertical longitudinal section taken on line 3—3 Figure 2.

Figure 4, is a vertical transverse section taken on the correspondingly numbered lines 25 in Figure 3.

Similar characters of reference indicate like parts in the several figures of the drawings:—

The numeral 10 represents the chassis of 30 the ice cream wagon which in the present instance is constructed as part of a gas-engine driven automobile. Upon the front part of this chassis is mounted the usual driver's cab

11 and upon the rear part thereof a housing 35 12 is arranged which may be divided into various compartments to suit the particular purpose for which the same is to be used.

As shown this housing has a front refrigerating compartment or chamber 13 upon the 40 bottom 14 of which cans containing ice cream to be delivered are supported and about midway of the height of this compartment contains a horizontal rack 15 adapted to support ice cream in brick form packed

45 in cartons, crates and the like. In rear of the refrigerating compartment is arranged the ice compartment 16 in which a supply of ice is stored for use in packing the ice cream in tubs when delivering the same to

50 the trade, additional compartments being provided for holding a supply of salt and to store empty cans which are returned by the customers.

The several walls of the refrigerating

compartment are normally tight so as to prevent the escape of the cold air therefrom and maintain the same at a low temperature. The bottom 17 of the ice storage compartment, however, is constructed of slats which are separated by intervening passages 18 through which the water of the melting ice can escape into a pan 19 below the slats and then conducted to the rear of the chassis so as to keep the water and brine away from the running gear of the automobile and prevent corroding the same which otherwise would occur.

When it is desired to wash out the refrigerating compartment a plug 20 is removed from a drain passage 21 in the lower part 70 of the rear wall 22 of the refrigerating compartment which separates the same from the ice compartment whereby the wash water can flow from the bottom of the refrigerating compartment into the ice compartment and 75 then into the pan to the rear of the car. The cans and boxes containing ice cream are introduced into the refrigerating compartment and removed therefrom through a doorway 23 in one of its longitudinal walls 24 which doorway is normally closed by a door 25. This door, as well as the bottom, and walls of the refrigerating chamber are so constructed that the same have a heat insulating 80 capacity, this being accomplished by arranging cork 26 between inner and outer shells 27, 28 of these members.

The means for maintaining the interior of the refrigerating compartment at a low temperature in accordance with my invention 90 are constructed as follows:—

Arranged within the upper part of the refrigerating chamber is a brine tank which has a main elevated front part 29 adapted to contain the main part of the refrigerant 95 and a depressed rear part 30 forming a sump or catch basin in which the sediment of the refrigerant is adapted to gather and from which the same may be removed. This tank is constructed of suitable sheet metal, preferably copper to avoid corrosion and the same is of rectangular form in horizontal section but its circumferential dimension is less than the internal dimensions of the refrigerating chamber so that all four side walls of the tank are spaced apart from the walls of the refrigerating chamber so that the outer sides 100 of the tank walls and the under side of its

- bottom are exposed to the interior of the refrigerating chamber and thereby produce the maximum cooling effect of the refrigerant in the tank on the contents of the refrigerating chamber. The brine tank is removably supported in its operative position by connecting the upper edges of its walls by bolts 31 with the inner side of a frame 32 on the upper ends of the refrigerating compartment walls, whereby this tank may be detached from these walls and removed upwardly out of the refrigerating compartment for the purpose of inspecting or repairing the same.
- 15 Normally the top of the brine tank is closed by a horizontal top 9 which is detachably connected with the top frame 32 of the refrigerating compartment by means of bolts or screws 33 and ice and salt for the formation of brine, or other refrigerant is introduced into this tank through a filling opening 34 in the top, which opening is normally closed by a lid 35, said top and lid being of heat insulating construction the same as the side walls and bottom of the refrigerating compartment to prevent temperature radiation through the same.
- 19 Transversely in the lower part of the brine tank, and preferably only over the elevated front part of its bottom, a plurality of horizontal cooling or air circulating pipes 36 are arranged and mounted at their opposite ends on the longitudinal walls of the tank, so as to communicate with opposite sides of the upper part of the refrigerating compartment. By means of this construction the air in the upper part of the refrigerating compartment is free to pass back and forth through the pipes 36 and thus aid in reducing the temperature of the same and increasing the refrigerating effect on the contents of the refrigerating chamber. As the chassis rocks crosswise and tilts forwardly and backwardly during transportation of the truck the swashing of the brine causes the same to come in contact with all parts of the bottom and walls of the tank and the pipe extending therethrough and thus impart the maximum cooling effect of the refrigerant to the air in contact with these surfaces and producing a uniform lowering of the temperature in the adjacent part of the refrigerating compartment. During this agitation of the brine any sediment therein gradually works its way into the catch basin or sump 30 in the rear part of the tank from which it can be more conveniently removed owing to the absence of any cooling pipes therein.
- 20 In addition to fastening the tank at its upper edge to the upper frame of the walls of the refrigerating compartment the same is supported on its under side by a plurality of horizontal supporting bars 37 engaging transversely with the underside of the tank

and suspended at their opposite sides by hangers or rods 38 from the frame 32, as shown in Figures 2, 3, and 4.

The brine is maintained at such a level in the tank so as to partly submerge the air 70 circulating pipes 36 and when it rises above this line the surplus escapes through the upper end of an overflow pipe 39 which preferably extends upwardly through the bottom of the depressed part of the tank and 75 is provided at its upper end with a screen 40 to prevent the escape of any large foreign matter therethrough and possibly clogging the passages with which this overflow connects. The brine which escapes from the 80 tank through the overflow pipe 39 passes downwardly through a cooling coil 41 which is arranged along the rear wall 22 of the refrigerating chamber so that this brine is compelled to give its cooling effect to the 85 air within this chamber. In order to retard the escape of the brine from this coil the lower end of the same is connected with a stand pipe 42 which extends upwardly from the lower end of the coil within the refrigerating compartment and connects with the 90 upper end of a discharge pipe 43 having its lower end terminating over the pan 19 so that the latter receives the spent brine and delivers the same with the melted ice water 95 at the rear of the chassis. By this means the overflow brine is compelled to lay in the coil and the stand pipe 42 up to the upper end of the latter before it can finally escape so that practically all of the cooling effect 100 of the brine is abstracted therefrom and utilized for reducing the temperature in the refrigerating compartment before the brine is permitted to escape. The discharge pipe 105 43 is preferably arranged in rear of the wall 22 and the connection between the upper end of the stand pipe and discharge pipe extends through this wall as shown in Figures 2 and 3.

When it is desired to flush out the sump or catch basin for removing any sediment which may have accumulated therein a waste or flush pipe 45 is opened which pipe communicates at its upper end with the bottom of the sump and terminates at its lower end 110 over the pan 19 below the ice chamber and is provided with a hand operated valve 46. The lower part of this flush pipe and its valve 46 are arranged in the rear of the wall 22. For the purpose of protecting the 115 discharge pipe 43 and the flush pipe from the ice on the ice chamber the same are enclosed in a small protecting chamber 44 arranged in one corner of the ice chamber, access to this protecting chamber for manipulating the hand valve 46 being afforded through a doorway 47 in the adjacent longitudinal wall of this chamber which is normally closed by a door 48, as shown in Figures 2 and 3.

When it is desired to drain the cooling coil in the refrigerating chamber this can be done by removing a plug 49 in the lowermost part of this coil; upon removing this plug the brine from the coil flows to the bottom of the refrigerating chamber and passes thence through the drain passage 21 into the pan. To prevent any large solid matter from passing into the flush pipe the 10 upper end thereof is covered by a screen 50, as shown in Figures 2 and 3.

This refrigerating apparatus enables an exceedingly low temperature to be maintained in the refrigerating chamber by the 15 expenditure of a comparatively small amount of ice and liquid, or other refrigerant, and thus effects a considerable economy in the cost of delivering ice cream or the like from a plant to customers which are located at different points and thus require the refrigerating chamber to be opened at frequent intervals in making deliveries. Furthermore this construction is very compact so that the maximum amount of space

is available for carrying containers of the 25 commodity which is being dispensed. Moreover the several parts are so organized that the same are readily accessible and also removable for inspection, cleaning and repairing.

30

I claim as my invention:—

A refrigerating apparatus comprising a refrigerating compartment adapted to receive the articles to be cooled, a refrigerating tank arranged in the upper part of said compartment and having an elevated part and a depressed part, said elevated and depressed parts being arranged side by side, a plurality of air pipes arranged within the tank above the elevated part of the same 35 while the space above the depressed part thereof is devoid of such pipes, an overflow pipe having an inlet arranged within the tank and in line with the center of said pipes, and a drain pipe having an inlet 40 opening into the tank at the bottom of the depressed part thereof.

FREDERICK MEYER.
